Primary Examiner—Catherine Tuttle*(74) Attorney, Agent, or Firm*—Greenberg Traurig, P.A.(57) **CLAIM**

The ornamental design for the slider device display package unit, as shown and described.

DESCRIPTION

FIG. 1 is a top front perspective view showing my new design for a slider device display package unit in its assembled state;

FIG. 2 is a left side elevational view thereof;

FIG. 3 is a front view thereof;

FIG. 4 is a top elevational view thereof;

FIG. 5 is a right side elevational view thereof;

FIG. 6 is a rear side view thereof;

FIG. 7 is a bottom view thereof;

FIG. 8 is an opened and exploded perspective view thereof;

FIG. 9 is an inverted perspective view showing the opposing sides of the exploded components in FIG. 8; and,

FIG. 10 is an opened perspective view showing the outer package and inner tray elements in their assembled state.

The broken lines showing the slider device contained within the display package unit are for illustrative purposes only; and form no part of the claimed design.
